Primary Examiner — Lauren D McVey*Assistant Examiner* — Elisa Maria Pujals**CLAIM**

I claim the ornamental design for a phantom tyrannosaurus toy, as shown and described.

DESCRIPTION

FIG. 1 is a left top perspective view of a phantom tyrannosaurus toy;

FIG. 2 is a front elevation view of FIG. 1;

FIG. 3 is a rear plan view FIG. 1;

FIG. 4 is a left view FIG. 1;

FIG. 5 is a right view FIG. 1;

FIG. 6 is a top plan view FIG. 1; and,

FIG. 7 is a bottom plan view FIG. 1.

The broken lines shown on the drawings depict portions of the phantom tyrannosaurus toy that form no part of the claimed design.
